UNITED STATES PATENT OFFICE.

WILLIAM H. BOZARTH, OF VINELAND, NEW JERSEY.

OIL BURNER FOR STOVES.

Application filed July 26, 1921. Serial No. 487,714.

To all whom it may concern:

Be it known that I, WILLIAM H. BOZARTH, resident of Vineland, in the county of Cumberland and State of New Jersey, citizen 5 of the United States, have invented certain new and useful Improvements in Oil Burners for Stoves, of which the following is a specification.

My present invention relates to oil burners 10 for stoves, and particularly to a burner structure to be fitted in the standard type of kitchen range or cook stove.

An object is to provide a burner which can be readily fitted in place in a stove and which 15 will heat the stove top and also the oven after the manner intended in the use of coal, wood, or like fuel.

Another main object is to provide a burner and generator structure which are so associated that the gas is discharged to a central 20 manifold from which the gas passes to the two stove burners and to a burner supplying heat to the generator.

A further object is to provide a burner 25 of this type which is so constructed that oil supplied to the burner is converted into gas which gas supplies the flame.

A still further object is to so construct the 30 parts that the supply of gas can be directed in full volume to either the burner heating the stove top or the oven burner, or these burners can be operated together.

Another object is to provide for the supply 35 of steam with the gas to thus give a better mixture and guard against the formation of carbon, and to arrange for generation of the steam by utilizing heat resultant from the operation of the burner.

Yet another object lies in providing for a proper supply of steam and oil, controlled 40 by a single valve, during the operation of the burner, and in arranging for the supply of oil alone for starting the burner.

Yet a further object resides in providing a gas discharge from the generator so arranged 45 that any particles of extraneous matter will be held back and danger of clogging is thus obviated.

With these and other objects in view, which will be apparent from the drawing, specification and claims, this invention includes certain novel features of construction and combinations of parts which will now be set forth.

In the drawings:

Figure 1 is a top plan view of a burner

constructed in accordance with my invention.

Fig. 2 is a view in elevation looking from the inner side of the burner.

Fig. 3 is a view similar to Fig. 2 with the base and oven heating burner removed.

Fig. 4 is a sectional view on line 4—4 of Fig. 2.

Fig. 5 is a vertical sectional view on line 5—5 of Fig. 2.

Fig. 6 is a horizontal view through the 65 case of the generator burner showing the arrangement of the steam generating coil.

Fig. 7 is a sectional view through the gas distributing manifold.

Fig. 8 is a fragmentary sectional view 70 through the air box and gas discharge end of the generator.

Fig. 9 is a horizontal sectional view through the oil and steam control valve.

Fig. 10 is a vertical sectional view through 75 the structure in Fig. 9.

The structure is supported on the two base or leg members 1 and 2, the oven heating burner 3 being mounted directly on the leg members and the top burner 4 being carried 80 by a gas manifold 5 which is supported by the leg members.

The top burner consists of the two elongated burner sections 5 and 6 which have the circular openings and seats 7 formed along their length to receive perforated burner discs 8 of refractory material, screens 9 being mounted beneath the burner discs and these discs being set to project above the top of the burner members.

The oven heating burner 3 consists of an 90 elongated case having a plurality of openings 10 in which the perforated burner discs 11 are seated after the manner of the discs 8, screens being also provided beneath the discs 11. In use the burner members 3, 5, 95 and 6 are filled with gas and the screens beneath the burner discs screen this gas as

it passes to the burners and at the same time prevent the flame from carrying back to cause backfiring. The burner 3 is preferably 100 made curved on its outer and top edges, and the recesses 10 are so formed that burner discs 11 are disposed at an angle, this arrangement being made to direct the flames outwardly at an angle and to thus heat the 105 oven at the proper point.

Between the sections 5 and 6 of the top burner 4 a gas generator tube 12 is disposed, this tube being of thin brass or other suitable material and having a core 13 therein 110

to carry the oil. A generating burner 14 is disposed beneath the generator tube 12 and is provided with the longitudinal burner slots 15, a central slot being preferably 5 formed directly beneath the generator tube and a slot being provided on each side of the center so that the flame will strike and curl around or envelop the tube to heat all sides. Wicks 16 are provided for starting 10 the generator.

At its discharge end generator tube 12 has a box 17 secured in place, this box being formed with a depending portion and having a central baffle wall 18 extending down 15 from its top into this depending portion. The gas discharge opening 19 is on the opposite side of the baffle wall 18, and as this opening is extremely fine the volume of gas in box 17 is more or less quiet so that 20 any particles will settle into the lower end where the gas passes beneath baffle wall 18, and thus danger of the discharge opening 19 or the burners being clogged is obviated.

The gas settling and discharge box is fitted 25 in an opening 20 provided in an air box 21, which air box is open at 22 to the atmosphere. A curved gas supply pipe 23 is connected to open into the air box in line with the gas discharge opening 19 of box 30 17, the space between the opening 19 and the entrance to pipe 23 being sufficiently wide that a proper mixture of gas and air will be accomplished within the air box 21. The pipe 23 is curved downwardly and inwardly and is connected with the manifold 5 so that gas generated in tube 12 and mixed with air in box 21 is supplied and discharged directly into the manifold.

This manifold, as best shown in Figs. 40 5 and 7, has branches 24 and 25 which lead to and connect with the two portions 5 and 6 of the top burner 4, a branch 26 which connects with the oven burner 3, and a branch 27 which leads to the generator burner 14. By this arrangement the manifold has connection to supply gas to each of the burners. The generator burner 14 will be kept in full flame continuously during the use of the burner, and any control of 45 the gas supply at this point will be accomplished through manipulation and regulation of the oil supply, however it is desirable that provision be made for directing and varying the flow of gas to the burners 50 5, 6, and 3, and with this in mind I provide butterfly valves 28, 29, and 30 in the branches 24, 25, and 26. As shown in Fig. 7, these valves are to be set in such a manner that when valves 28 and 29 are open valve 30 55 will be closed, and the reverse, an intermediate position being calculated to give a full flow through all of the branches. To accomplish this manipulation of the valves I provide operating arms 31, 32, and 33 upon 60 the valve stems, with a push rod 34 connect-

ed to operate the valves 28 and 29 and a link 35 coupling valve 30 to be moved therewith. It has been found by repeated and exhaustive tests that a butterfly valve gives excellent results in this connection as the 70 operation is single and there is no objection to leakage which will maintain a small flame at the burner when the valve is closed. Other valve structure and operating mechanism might however be used in accomplishing 75 this result.

While the box 17 will catch foreign matter, a blow-off valve 36 might be connected in the bottom of the manifold for blowing off condensation. Also any type of safety-valve might be provided in the steam pipe 39 to guard against excessive pressure.

While this burner will operate efficiently and economically upon oil being supplied to the generator, it has been found advantageous to maintain a supply of steam as this accomplishes a better gas mixture and prevents formation of carbon. During the operation of the burner hot gas is supplied to the generator burner 14, and a coil 37 90 is arranged within the case of the burner 14 to generate steam. Water is supplied through a pipe 38 to the coil 37, and the steam is discharged through a steam pipe 39. A valve casing 40 is connected by a pipe 41 with generator tube 12, and this valve casing has a needle valve 42 controlling the main passage thereof. Oil and steam branches 43 and 44 communicate with the main passage, opening through the seat of valve 42. Connection is made through an oil pipe 45 from a suitable oil supply, and the steam pipe 39 connects with passage 44. By this arrangement the flow of oil and steam will be simultaneously 105 controlled and the proper proportions will be maintained, it of course being understood that valves can be introduced in pipes 39 and 45, or at other suitable points where adjustments may be desired or necessary.

In starting operation of the burner oil only will be supplied to the generator tube, and for starting this oil may be supplied through a branch 46 leading to the main passage of the valve casing, an oil pipe 47 115 being connected with the passage, and a needle valve 48 controlling the flow of oil therethrough.

In the use of my improved structure the burner will be fitted in the fire box of an 120 ordinary type of kitchen range or cook stove, with push rod 34 extending through one of the draft slots and pipe 44 run into the burner through any suitable opening. In starting the burner a volatile liquid is 125 poured onto the wicks 16 and when the generator tube 12 is properly heated valve 48 is opened to supply oil from pipe 47. Gas is generated and is supplied to burner 14, and also to burners 3, 5 and 6. As the 130

heated gas flows into the casing of burner 14 around coil 37 steam is generated therein, and when the proper heat is attained valve 42 is opened and valve 48 is closed. Steam and oil are then supplied through pipe 41 to generator tube 12 and the burner is continued in operation. By manipulation of push rod 34 the butterfly valves 28 and 29, as a pair, and valve 30 are shifted as hereinbefore described to give a full supply of gas to either the top or the oven burner, or to leave the passages open to both.

While, in the foregoing, I have described specific embodiments, and have mentioned only certain possible modifications, it will be appreciated that in practice I do not limit myself to such specific details as herein set forth, but may resort to any practical modifications falling within the scope of the invention as defined in the appended claims.

I claim:

1. An oil burner for cook stoves including with a gas consuming burner to heat the top of the stove, a gas consuming burner to heat the oven, a valve arrangement by which the supply of gas is opened to each of the burners and the gas is cut off from one burner while the remaining burner is in full flame, and a single operating means by which the valve mechanisms are simultaneously moved and set.

2. An oil burner for cook stoves including with a gas consuming burner to heat the top of the stove, a gas consuming burner to heat the oven, a valve arrangement by which the supply of gas is opened to each of the burners and the gas is cut off from one burner while the remaining burner is in full flame, a common manifold supplying gas to said burners, a single operating means by which the valve mechanisms are simultaneously moved and set and a generator discharging gas to the manifold.

3. An oil burner for cook stoves including with a gas consuming burner to heat the top of the stove, a gas consuming burner to heat the oven, a valve arrangement by which the supply of gas is opened to each of the burners and the gas is cut off from one burner while the remaining burner is in full flame, a common manifold supplying gas to said burners, a single operating means by which the valve mechanisms are simultaneously moved and set, a generator discharging gas to the manifold, and a gas burner for said generator receiving gas supply from the manifold.

4. An oil burner including with top and side burners, a gas manifold supplying to said burners, generator structure to supply gas to the manifold, means to direct the full volume of gas in the manifold to either of said burners selectively and to both burners

in equal volume as desired, a generator burner also supplied from the gas manifold, and a steam generating coil within the generator burner.

5. An oil burner including with gas consuming burner generator structure to supply gas to said burner, a valve casing connected with the generator, a needle valve in said casing, and oil and steam supply pipes connected with the casing in communication with passages opening through the valve seat.

6. An oil burner including with gas consuming burner generator structure to supply gas to said burner, a valve casing connected with the generator, a needle valve in said casing, oil and steam supply pipes connected with the casing in communication with passages opening through the valve seat, and an independent oil supply to the casing to be used for starting the generator.

7. An oil burner including with gas consuming burners, generator structure to volatilize oil to supply gas to said burners, an air box through which the gas passes to take up the air on its way to the burner, and a settling box into which the gas is discharged from the generator and in which the gas is confined in its passage to the burner to thus permit foreign matter or particles in the gas to settle.

8. An oil burner including with top and side gas consuming burners, a generator structure to volatilize oil to supply gas to the burners, a generator burner, a manifold to which the gas is supplied from the generator provided with branches leading to the top and side burners and the generator burner, butterfly valves controlling the passages to the top and side burners, a single valve operating means to close the passage to one burner when the passage to the other is open and to set the valves in intermediate positions where gas is supplied to all the burners.

9. An oil burner including with gas consuming burners, a gas generator, a generator burner, a manifold to which the gas is discharged from the generator connected to supply gas to the main and generator burners, a steam generating coil within the casing of the generator burner, a valve casing connected with the generator and having oil and steam passages opening thereinto through the valve seat, a connection from the steam generating coil to the steam passage, an oil supply connection to the oil passage, and a needle valve to close against the seat within the casing and to give equal control at the oil and steam passages.

In testimony whereof I hereunto affix my signature.

WM. H. BOZARTH.
